APPARATUS FOR SHEARING METAL

Aaron Marofsky, Chelsea, Mich.

Application November 28, 1936, Serial No. 113,232

5 Claims. (Cl. 164—42)

My invention relates to apparatus for shearing metal and the object of my improvement is to perfect the operative construction, and to facilitate the presentation of the material to the apparatus and its disposition after it has been acted upon.

In the accompanying drawings, Figure 1 is a side view of an apparatus embodying my invention.

10 Figure 2 is an elevation looking from the right of Figure 1, the jaw being shown as closed down to cutting position.

Figure 3 is a sectional elevation on the line 3—3, Figure 2, the frame 61 being shown turned 15 down in position to receive the work 64, thereon.

Figure 4 is a detail perspective view, illustrating the take-up construction of the bearing for the main shaft.

Figure 5 is a sectional elevation on the line 20 5—5, Figure 1, looking in the direction of the arrows.

Figure 6 is a detail sectional view showing the connection of the actuating mechanism with the jaw.

25 Figure 7 is a detail sectional view on the line 7—7, Figure 1.

Figure 8 is a detail elevation of a portion of the apparatus adjacent to the cutter edges looking from below Figure 9.

30 Figure 9 is a plan view, the carrier trough and carrier being omitted.

Figure 10 is a detail section on the line 10—10, Figure 9.

Referring now to the reference numerals on 35 the drawings:—2 denotes the frame of the machine resting upon blocks 51, and 1 indicates a swinging jaw secured to a shaft 3, adapted to oscillate in bearings in the upper end of upright members projecting from the frame 2. Numerals 66 (Figure 5) is a key securing the shaft 3, to the jaw 1. Numerals 9, 9 denote grease conduits opening at the ends of the shaft 3, and at the periphery of said shaft within its bearings.

40 The ends of the shaft 3, are screw threaded, and caps 4, 4 internally screw-threaded engage the threads on the end of said shaft. The caps 4, 4 are adapted at 65, 65 to be engaged by a wrench, for adjustment or removal. The numeral 8 denotes a part shaped to form the lower portion of the bearing for the shaft 3. The lower surface of said part tapers inwardly and fits against and is adjustable along the corresponding wall of the opening in the frame 2, through which said shaft passes (Figures 4 and 5). Numerals 5, 5 designate plates encircling

the ends of the shaft 3, and adapted to bear against the surface of the frame 2, and outer ends of the portions 8, 8. Bolts 6, 6 pass through said plates and in screw-threaded apertures in the frame 2. Numerals 7, 7 denote 5 bronze plates interposed between the side surfaces of the jaw 1, and the adjacent surfaces of the frame 2. The bolts 6, press the bronze plates 7 against jaw 1 thus serving to adjust the jaw laterally. The plates 7 have grease cups 10, and 10 passages to supply grease to the contiguous surfaces of said jaw and plates. Numerals 11 indicate wedges connected to the frame 2 by bolts 12, which serve to force said wedges between the plates 7 and adjacent surfaces of the frame 2 15 and to press said plates against the sides of the jaw.

Power is communicated to the cutting apparatus by means of a belt 40 (Figure 9) passing over a pulley 69 upon the shaft 41, mounted in 20 bearings 42—42. A spring 44, surrounding the shaft 41 between the bearings 42 presses collars 45—45 against said bearings and tends to keep the grease in said bearings. 22, 22 are flywheels 25 on the shaft 41. 43, 43 are pinions on the shaft 41. Numerals 38 denotes a shaft extending transversely across the frame 2 and adapted to turn in bearings 32 thereon. Numerals 21, 21 designate gear wheels on the outer ends of said shaft with which the pinions 43—43 mesh. Numerals 30 33, 33 (Figure 6) denote two arms, and 39 a connecting pin, of a crank upon the shaft 38. Numerical 29 indicates a connecting rod pivoted at its lower end upon the pin 39, and at its upper end upon a pin 36, extending transversely 35 through the walls of a slot in the end 30, of the jaw 1. Bronze plates 37 are interposed between the sides of the connecting rod 29, at its upper end and the side walls of said slot in the jaw 1. Set screws 31, 31 pass through the walls of said 40 slot and engage the plates 37 to press the same against the connecting rod to adjust it laterally and thus obviate any lost action.

Numerals 26, 26 denote posts, integral with the frame 2 and rising vertically therefrom upon 45 opposite sides of the jaw 1. A bolt 34, (Figure 7) connects the upper ends of the posts 26 and is fitted with adjustable nuts 27, at each end. The jaw 1 has steel plates 28, welded to its sides which slide upon the bronze plates 35. Set- 50 screws 71, press bronze plates 35 against the steel plates 28 which also tend to move the jaw 1 laterally.

The jaw 1 has a knife 70, which shears past knife 70a on the frame 2 (Figures 1 and 2).

The gear wheels 21, mesh with pinions 20 on a transverse shaft 23, fitted with a sprocket wheel 14, at its outer ends. The numeral 13 denotes a shaft parallel to the shaft 23, having sprocket wheel 67 at its outer ends. Numeral 19 designates a sprocket chain passing over and connecting the sprocket wheels 14 and 67.

Numeral 15 indicates a bevel gear on the shaft 13. Numeral 18 denotes a table at one side of the frame 2 at the delivery end of the apparatus. Numeral 25 denotes a roller beneath the table 18, its shaft extending at right angles to the shaft 13, and having a bevel gear 24. Numeral 16 (Figures 2 and 9) designates a conveyor passing around, and actuated by a driving roller 25. The table 18 has slots 52 in its upper wall and the conveyor is provided with prongs 17 which pass through said slots to engage any object on the table 18. Numeral 72 denotes a curved delivery surface extending from the cutter 70a to the table 18.

Numeral 47 designates a table connected to the frame 2 by lugs 50 pivoted to the upper ends of vertical levers 48—which levers are secured to bolts 49 at their lower ends, that engage the frame 2. As said bolts are loosened levers 48 swing down lowering the table as illustrated in broken lines (Figure 8).

The following apparatus is used for handling large parts such as automobile frames. Numeral 54 (Figures 1 and 3) denotes a trough in the floor 68. Numeral 56 indicates a plate supported in the trough 54 by springs 55. Numeral 56a denotes a guide plate for the side of the carrier which may be adjusted laterally by hand screws 51. Numeral 58 designates a carrier provided with wheels 62, resting upon and adapted to travel longitudinally on the plate 56. The carrier 58 has a rigid fence 59 at one end and side 40 to prevent work falling therefrom. Numeral 61 indicates a movable frame pivoted at 60 to the side of the car 58, so as to swing in a vertical plane. The frame 61 is turned down and the work placed thereon as shown in Figure 3. The frame is then turned up dropping the work into the carrier which is then manually pushed forward, and the work 64 is made to lean over to bring a portion of it between the cutters (Figure 1). The fragments 73 slide down the incline 72 50 onto the table 18, from which they are removed by the prongs 17 on the conveyor 16.

Smaller articles are placed upon the table 47, and passed therefrom to the cutters. With large parts there is apt to be lost motion between the work and the lower cutter as the work yields to the descending jaw 1, the springs 55 yield 5 to the thrust.

Numerals 63 denote chains secured to the frame 2, and the carrier 58, to limit the travel of the latter.

What I claim is:

1. In an apparatus of the kind described, an oscillating jaw, two posts located opposite to each other adjacent to the sides of said jaw and spaced from the pivotal axis of said jaw, and means for adjusting the distance apart of said posts. 10

2. In an apparatus of the kind described, an oscillating jaw, two posts located opposite to each other adjacent to the sides of said jaw and spaced from the pivotal axis of said jaw, and means for adjusting the distance apart of said posts, a plate interposed between one of said posts and the side of said jaw and means for adjusting said plate at right angles to the plane of oscillation of said jaw. 15

3. In an apparatus of the kind described, the combination of a cutter, a trough-like structure passing transversely in front of said cutter, a plate in said structure forming a way for a carrier, springs supporting said plate, and a carrier adapted to travel upon said plate. 20

4. In an apparatus of the kind described, the combination of a cutter; a plate forming a way for a carrier and extending transversely in front of said cutter adjacent thereto; springs supporting said plate; and a carrier adapted to travel upon said plate, substantially as and for the purpose described. 30

5. In a machine for shearing automobile frames, an oscillating jaw having a shaft; a bearing for said shaft, two posts located opposite to each other adjacent to the sides of said jaw and means for adjusting and fixing the distance apart between said posts, said jaw having a shearing edge; a stationary shearing edge adapted to coat with said shearing edge upon said jaw; and a spring-supported plate adapted to receive an automobile frame and hold a portion thereof adjacent to said stationary shearing edge and in the line of travel of said shearing edge on said jaw. 40

AARON MAROFSKY. 50
